US00D612316S

(12) **United States Design Patent**
Sanschagrin et al.

(10) **Patent No.:** **US D612,316 S**
(45) **Date of Patent:** **** Mar. 23, 2010**

(54) **CENTRAL PORTION OF A WHEEL HUB**

(75) Inventors: **Stephane Sanschagrin**, St-Hyacinthe (CA); **Jean-Philippe Crepeau**, Bromont (CA); **Christopher Rudwal**, Granby (CA)

(73) Assignee: **Bombardier Recreational Products Inc.**, Valcourt (CA)

(**) Term: **14 Years**

(21) Appl. No.: **29/278,856**

(22) Filed: **Apr. 12, 2007**

(51) **LOC (9) Cl.** **12-16**

(52) **U.S. Cl.** **D12/210**

(58) **Field of Classification Search** D12/204-213; 301/37.101, 64.101, 65, 64.201; 280/731; 40/57

See application file for complete search history.

(57) **CLAIM**

The ornamental design for a central portion of a wheel hub, as shown and described.

DESCRIPTION

FIG. 1 is a perspective view from the front and left side of the central portion of a wheel hub according to our design; and, FIG. 2 is a front elevational view thereof.

Throughout the Figures, broken lines showing structure are for illustrative purposes only and form no part of the claimed design.
